INVENTOR.

UNITED STATES PATENT OFFICE.

JOHN MURPHY, OF MEMPHIS, TENNESSEE, ASSIGNOR OF ONE-HALF TO GEORGE P. SCHLOCKER, OF MEMPHIS, TENNESSEE.

PICKER-HEAD.

1,229,121.

Specification of Letters Patent. Patented June 5, 1917.

Application filed June 29, 1916. Serial No. 106,719.

To all whom it may concern:

Be it known that I, JOHN MURPHY, a subject of the King of Great Britain and Ireland, residing at Memphis, in the county 5 of Shelby and State of Tennessee, have invented certain new and useful Improvements in Picker-Heads, of which the following is a specification that will enable those skilled in the art to which the invention 10 pertains to make, construct, and use the same, reference being had therein to the accompanying drawings.

The invention relates to those picker-heads of cotton-harvesting machines that 15 are used in association with flexible pipes in which suction is maintained to induce movement of fiber picked by the heads therefrom to a receptacle, and it has particular reference to picker-heads in which 20 rotating brushes operate to dislodge the fiber from the bolls.

It is an object of the invention to provide simple and efficient means, located entirely within the head, whereby there is 25 removed from the brushes such fiber as may tend to adhere thereto, so that all the picked fiber is rendered easily susceptible of being moved through the flexible tube to the place of deposit and the brushes are prevented 30 from becoming clogged and thereby having their picking action retarded.

The invention also provides guard-fingers 35 in association with the picking-brushes for preventing trash and the like from being drawn into the head by the brushes and for assisting in clearing adhered fiber from the brushes.

Further, the invention makes certain other 40 improvements in the details of devices of this character, whereby their efficiency is increased, the facility of use is enhanced, and access may easily be had to the interior 45 for the purpose of cleaning and repair, as will appear from the following explanation of the construction and use of the device.

When read in connection with the description herein, the details of construction and arrangement of parts contemplated by the invention will be apparent from the accompanying drawings, forming part hereof, 50 wherein an embodiment of the invention is disclosed, for purposes of explanation.

While the disclosures herein now are considered to exemplify a preferable embodiment of the invention, it is to be under-

stood that it is not the intention to be limited necessarily thereto in interpretation of the claims, as alterations and adaptations within the limits of the claims can be made without departing from the nature and 60 spirit of the invention.

Like reference-characters refer to corresponding parts in the views of the drawings, of which—

Figure 1 is a top view, a portion of the 65 top of the casing being broken away;

Fig. 2 is a side elevation, a portion of the side of the casing being broken away;

Fig. 3 is a sectional view on the line 70 3—3, Fig. 2;

Fig. 4 is a sectional view on the line 75 4—4, Fig. 1;

Fig. 5 is a sectional view on the line 5—5, Fig. 3;

Fig. 6 is a sectional view on the line 75 6—6, Fig. 3;

Fig. 7 is a sectional view on the line 7—7, 80 Fig. 4;

Fig. 8 is a sectional view on the line 8—8, 85 Fig. 3; and

Fig. 9 is a view of the receiving end of the head.

Having more particular reference to the drawings, 10 designates a flexible tube leading to a receptacle at one end in a cotton-picking machine (not shown), on which latter there is any suitable means whereby suction is induced in the tube to cause movement of picked cotton to the receptacle, the tube being adapted to be carried in its free 90 end portion by a person engaged in picking cotton. The tube at its free end envelops and is held by clamping-rings 11 on a contracted cylindrically-shaped discharge end of a picker-head 12.

The picker-head includes a casing formed of abutting upper and lower sections 12' and 12" held together with a substantially fluid-tight joint in an approximately median plane by the action in laterally-extending exterior registering projections 13 of machine-screws 14 or the like. Side walls 15 of the casing widen from each other from a place near the discharge end of the head and then continue in substantially parallel relation nearly to the entrance of the mouth of the head, and at that end each wall has an inwardly-projecting vertically-disposed abutment 16 with a plane outer face, the abutments being oppositely located. A side 110

- mouth-wall 17 forms an extension of each of the side walls 15, to which it is secured by an inwardly-extending flange 18 thereof held against the plane outer face of the abutment 16 by screws 19 or the like. Upper and lower bottom walls 20 and 21 continue in substantially parallel relation from the cylindrical portion of the discharge end of the head to a place removed from the entrance of the head, and a lower extension-wall 22 curves downwardly at this place from the lower wall 21 and thence continues in the original direction to the plane of the outer edge of the side mouth-walls 17. 15 From a place removed from the receiving end of upper wall 20 an upper extension-wall 23 extends upwardly and thence continues lengthwise of the head to the plane of the outer edges of the side mouth-walls 17. 20 It will be seen that the side walls 15 and 17 and the lower and upper extension-walls 22 and 23 comprehend an enlarged mouth of the picker-head, in which the picking mechanism hereinafter described is located; and 25 that the side walls 15 and the upper and lower walls 20 and 21 comprehend a throat smaller than the mouth leading from the rear portion thereof.

The picking mechanism is actuated by a 30 flexible shaft 24 rotated by any suitable means on the picking-machine. There is a boxing 25 on the upper wall 20 of the casing, and therein is a drive-shaft 26 connected to and rotated by the flexible shaft. A wall 35 23' extends upwardly from the wall 20 of the casing and thence forwardly to the wall 23, and these walls inclose a gear and shaft chamber. The drive-shaft extends into this chamber, and it has a pinion 27 fast on its 40 inner portion.

The pinion 27 is in mesh with a drive-gear 28 fast on a counter-shaft 29 extending transversely and horizontally of the upper portion of the head and journaled in the 45 side walls thereof. The gear 28 also is in mesh with a pinion 30 fast on the end of a vertical shaft 31 centrally positioned across the entrance of the throat and journaled in boxings 32 at the ends of the upper and 50 lower walls 20 and 21; and fast on this shaft, between the boxings, there is a clearer-wheel 33 having a plurality of radially-extending clearer-teeth 34 arranged in a plurality of circumferential rows. 55 The shaft 29 extends outside of one of the side walls 15 of the casing into a gear-chamber inclosed by a gear-cover 35 and the side wall, the cover being held in place by screws or the like 36. A pinion 37 with- 60 in the chamber is fast on the end portion of shaft 29, and this pinion is in mesh with a gear 38, which in turn meshes with a similar gear 39. The gears 38 and 39 are fast, respectively, on upper and lower 65 brush-shafts 40 and 41 extending trans-

versely of the mouth of the picker-head and arranged one above the other near the entrance of the mouth between it and the clearer-wheel 33, the axes of the brush-shafts being substantially at right angles to the axis of the clearer-wheel shaft. The shafts 40 and 41 are journaled in bearings 42 formed in and between the abutments 16 and the flanges 18, so that when the side mouth-walls 17 are withdrawn and the gear-cover 35 removed the shafts may be taken out. The shafts 40 and 41 carry picking-brushes 43 and 44, respectively, fast thereon between the abutments 16 and flanges 18. Each brush includes a series of clusters 45 of bristles or other suitable flexible material arranged in axial and circumferential rows. The brushes are so rotated in opposite directions that they move intersectingly toward the clearer-wheel, and the relative arrangement of the parts is such that during this rotation the axial rows of clusters of one of the brushes slightly intermesh those of the other at a place directly opposite to the clearer-wheel and in their movement brush against the teeth of that wheel. 70 80 85 90

In order to prevent entrance into the mouth of trash and the like, a plurality of guards 46 extend from the upper and lower 95 walls of the picker-head casing across the entrance between the circumferential rows of brush-clusters. The guards preferably are formed of strong wire loops secured to the casing-walls by screws 47, and the ends of those projecting in one direction nearly contact with those projecting in the other direction at a place opposite to the point of intersection of the brush-clusters. 100

When in use and suction being induced in the tube and head and the movable parts being rotated in the directions described, the operator touches the head at the entrance of the mouth against the fiber in cotton-bolls, the brushes engage and draw the fiber between them to the entrance of the throat into which it is drawn under the influence of the suction therein and thence through the flexible tube to the receptacle in the machine. Fiber that may have a tendency to adhere 110 to the brushes is removed therefrom by the clearer-wheel at the entrance of the throat and drawn therefrom through the throat. The successive brush-clusters continuing 115 their revolution continue to engage and pick 120 the cotton fiber.

The guards extending between the circumferential rows of brush-clusters prevent trash and the like from being drawn into the head. Further, the guards operate to 125 loosen from the clusters fiber adhering thereto that has not been removed by the clearer-wheel and such fiber thereby is rendered susceptible of being induced into the throat.

Access to the interior of the mouth may 130

be had for the purposes of cleaning, repair, and replacement of parts by removing the gear-cover and withdrawing the side mouth-walls as already described, and by removing 5 the guards, when the picking-brushes can be taken out and the clearer-wheel can be reached. Further access may be had to the interior by separating the upper and lower sections of the head on loosening the fasten- 10 ings thereof, and such separation may be made either with or without removal of the brushes.

Having thus described my invention, what I claim as new, and desire to secure by Letters Patent, is—

1. In a picker-head having a mouth and a throat leading therefrom, the combination of a drive-shaft mounted longitudinally and exteriorly of the head and extending inside 20 thereof, a pinion on the inner portion of said shaft, a drive-gear in mesh with said pinion, a counter-shaft on which said drive-gear is fast and mounted transversely of the head, a clearer-wheel shaft mounted sub- 25 stantially at right angles to said counter-shaft at the entrance of said throat, a clearer-wheel on said clearer-wheel shaft, a pinion fast on said clearer-wheel shaft in mesh with said drive-gear, oppositely-disposed brush- 30 shafts mounted in said mouth substantially at right angles to said clearer-wheel shaft, coöperating brushes on said brush-shafts in contact with said clearer-wheel, gears on said brush-shafts in mesh with each other, 35 and a gear on said counter-shaft in mesh with one of said brush-shaft gears.

2. A picker-head comprising a casing of abutting separable sections shaped to form

a contracted discharge end and an enlarged mouth and a throat smaller than the mouth 40 leading therefrom at the discharge end, rotatable picking-brushes in said mouth, a clearer-wheel in rear of said brushes at the entrance of said throat, and means whereby 45 said brushes and wheel are rotated.

3. A picker-head comprising a casing comprehending a mouth and having opposed walls extending nearly to the entrance of the mouth, abutments at the ends of said walls, and removable opposed wall-exten- 50 sions one attached to each of said abutments.

4. A picker-head comprising a casing comprehending a mouth and having opposed walls extending nearly to the entrance of the mouth, an abutment at the end of each of 55 said walls, a wall-extension for each of said walls, a flange on each of said extensions removably secured to one of said abutments, there being a bearing in and between each pair of abutting abutments and flanges, in 60 combination with a brush-shaft journaled in said bearings, a brush on said shaft and means whereby said shaft is rotated.

5. A picker-head comprising a casing shaped to form a contracted discharge end 65 and an enlarged mouth and a throat smaller than the mouth leading therefrom to the discharge end, rotatable picking-brushes in said mouth, a clearer-wheel at the entrance of said throat in rear of and having its axis 70 in a plane substantially at right angles to the axes of said brushes, and means whereby said brushes and wheel are rotated.

In testimony whereof, I affix my signature.

JOHN MURPHY.
